(57) **CLAIM**

The ornamental design for a square fire pit, as shown and described.

DESCRIPTION

FIG. 1 is a perspective view of a square fire pit.

FIG. 2 is a front view of the square fire pit of FIG. 1.

FIG. 3 is a back view of the square fire pit of FIG. 1.

FIG. 4 is a left side view of the square fire pit of FIG. 1.

FIG. 5 is a right side view of the square fire pit of FIG. 1.

FIG. 6 is a top view of the square fire pit of FIG. 1; and,

FIG. 7 is a bottom view of the square fire pit of FIG. 1.

The broken lines shown in the drawings are for the purpose of illustrating portions of the article that form no part of the claimed design.

1 Claim, 5 Drawing Sheets
